APPARATUS FOR ORBITAL FINISHING
John F. Rampe, 3417 Fairfax Road,
Cleveland Heights, Ohio 44118
Filed Nov. 5, 1964, Ser. No. 409,166
18 Claims. (Cl. 51—163)

This invention relates to the finishing of commercial parts by vibratory action, and more particularly to finishing apparatus of the orbital type.

In my application, Serial No. 261,981, filed March 1, 1963, and now Patent No. 3,191,348 dated June 29, 1965, I have disclosed an apparatus for orbital finishing in which pairs of part-carrying tubs or workpiece containers are mounted on opposite sides of a vibratory or rotary shaft and the carriage supporting the tubs is driven through a small orbital path. In my application Serial No. 357,212 filed April 3, 1964 for Finishing Apparatus, I have disclosed a vibratory type of orbital finishing machine which is capable of continuous operation as well as batch operation. The machines which are the subjects of the above mentioned applications are particularly adapted to relatively large batches of workpieces and accordingly are relatively large and expensive.

An object of this invention is to provide an improved orbital type vibratory finishing machine which is compact in construction and economical in operation.

Another object of this invention to provide a vibratory type orbital finishing machine which is relatively economical in construction and highly efficient in operation.

Briefly in accordance with aspects of this invention, I have discovered an improved orbital type vibratory finishing machine in which a carriage and a pair of flat plate counterpoises are mounted on a frame with a rotating shaft extending through the carriage and the counterpoise plates. Advantageously, the workpiece containing tub is mounted in a pair of trunions and held in this position by four bolts only two of each need to be released in order to manually tilt the tub for discharge of workpieces. On the opposite end of the carriage from the tub is a counter weight mounted on a suitable bracket, which counter weight is preferably at least as heavy as the weight of the tub without its workload. Advantageously, the carriage is supported by four pairs of shear type resilient bushings, one pair mounted on and projecting inwardly from each corner post of a rectangular frame. The apparatus is also provided with a counterpoise in the form of a pair of substantially flat plates, each mounted on a pair of cross members or cross braces of the rectangular frame and positioned within the frame in close proximity with the carriage. A rotary shaft is employed to produce the orbital movement and this shaft is rotatably mounted in the carriage and counterpoise plates and has opposed pairs of eccentric sections inwardly of the frame for rotating the carriage and the counterpoise plates in opposition to each other. Preferably the eccentricity of one pair of eccentric members is substantially equal to the eccentricity of the other pair of eccentric members, so that the carriage and the side plates or counterpoise plates will be driven through orbits of equal radius.

In accordance with the other aspects of this invention I provide an orbital type vibratory finishing apparatus with a generally rectangular frame in which cross members are provided between corner posts, which cross members are formed of angle members having inwardly extending surfaces horizontal and vertical surfaces interiorly of the horizontal surfaces. Shear type bushings are mounted on the vertical surfaces and project outwardly relative to, but are contained within, the frame supporting the counterpoise plates or side plates. A tub supporting carriage is mounted by resilient bushings of the shear type project-

2

ing inwardly from and mounted on the corner posts. With this arrangement the counterpoise and carriage are mounted within the frame and a pair of cover plates attached to and substantially coplanar with the opposite sides of the frame acts as a cover for the apparatus. A drive shaft is rotatably mounted in the counterpoise plates and the carriage and suitable driving motor is mounted on the top of the frame and connecting by a flexible belt to a pulley mounted on the end of the drive shaft. The vibratory apparatus includes a fluid flow system including a re-circulation system for recirculating a fluid containing an abrasive or a polishing compound. The fluid flow system is provided with means for separate flow controls permit automatic cycling of the mixture from the tub to a storage tank and return or permit fresh water to be flushed through the tub to a drain during the operating cycle.

Other objects and advantages relate to certain novel features of construction and combinations and arrangements of parts which provide economy in manufacture and operation. The invention is described in connection with the accompanying drawings forming a part of the specification and illustrating a preferred embodiment which represents the best known mode of practicing the invention.

In the drawings:

FIGURE 1 is a view in perspective of the finishing machine of the present invention;

FIGURE 2 is a side view of the machine of FIGURE 1 to an enlarged scale with portions of the machine removed and parts broken away;

FIGURE 3 is a side view of the embodiment of FIG. 1 taken from the left hand side thereof to the same scale as FIG. 2;

FIGURE 4 is a front elevational view of the embodiment of FIG. 1 partly broken away and partly in section, to the same scale as FIGS. 2 and 3;

FIGURE 5 is a view in perspective, to an enlarged scale, of the carriage of the apparatus for FIG. 1;

FIGURE 6 is a view in perspective showing the vibratory assembly of the apparatus for FIG. 1 and the vibratory assembly drive mechanism; and

FIGS. 7A and 7B are detailed views of the resilient shear-type mounting bushings showing examples of the carriage and counterpoise mountings, respectively.

Referring now to the drawing which shows one illustrative embodiment of the apparatus of this invention including a frame 10 on which is mounted for orbital vibratory motion a tub carriage 11 which supports a suitable workpiece tub or barrel 12. Mounted on the top of the frame 10 is an instrument control and driving mechanism assembly 13 including an instrument panel 14. Also mounted on the frame 10 for oscillation in an orbital path out of phase with the carriage 11 is a counterpoise including a pair of side plates 15, 16. The apparatus includes a solution recirculation and drain reservoir 20 mounted centrally of the base of the frame 10. Mounted on the instrument panel 14 a start-stop switch 17, a pump switch 18 and a timer 19.

As shown in FIGURES 2 and 4, an electric motor 22 is mounted in the instrument control and driving assembly 13 and motor 22 has an armature shaft 23 connected in driving relationship to a drive shaft 24 of the vibratory assembly. Drive shaft 24 is mounted centrally of the carriage 11 by means of a pair of bearings 25, 26 and has a pulley 27 splined or otherwise secured to one end thereof, which pulley is connected in driven relationship to a pulley 28 on the shaft 23 by means of a suitable flexible belt 30.

The pulley 28 is part of a variable speed drive which includes a sheave 33 secured to the shaft 23 and a slid-able

sheave 34 mounted for sliding movement relative to axis of the shaft 23, keyed to the shaft 23 to prevent relative rotation and biased by means of a suitable spring 35 toward sheave 33. The base of the motor 22 is secured to a pair of right angle brackets 38 by suitable means such as by bolts 39 and nuts 40. The right angle brackets 38 are drilled to provide two pairs of aligned apertures one pair of which encircle each of a pair of rods 42, 43 for sliding engagement such that the motor 22 may be moved from a forward to a rearward position along the rods 42, 43 i.e. transversely relative to the motor axis. The rods 42, 43 are each supported by a pair of right angle brackets such as the brackets 45, 46 which brackets are welded or otherwise secured to the top 44 of the frame 10. A threaded rod 48, only the end of which is shown, is rotatably mounted in angle brackets 45, 46 and threadably engages a right angle bracket, not shown, similar to the bracket 38 and mounted beneath the frame of motor 22. A band wheel 50 is secured to the end of rod 48 and rotation of the hand wheel 50 cause translation of the motor 22 along the rods 42, 43. Because the sheave 34 of pulley 28 is spring biased, it maintains pressure upon the belt 30. If the motor 22 is moved away from the pulley 27 i.e. in a rearwardly direction relatively to the instrument panel 14 then the pulley sheave 34 moves axially outwardly and the effective diameter of the driving pulley 28 is decreased thus causing the pulley 27 and shaft 24 to be driven at a slower speed. With this arrangement of variable pulley diameter, it is possible to employ a motor having a speed of the order of 3600 r.p.m. and to vary the speed at which the drive shaft 24 is driven between a speed of 900 and 1800 revolutions per minute. This will produce orbital vibration in the carriage 11 of 900 to 1800 orbits per minute, respectively. As a safety measure, the pulleys 27, 28 and the belt 30 are enclosed in a suitable belt guard 52.

The construction of the frame 10 is shown in detail in FIGURES 2, 3 and 4. As therein depicted, the frame includes a base member 55 to which is secured four uprights or legs 56, 57, 58 and 59. Each of the legs 56 through 59 are formed from right angle stock and are welded or otherwise secured to the base member or base plate 55 with the angles facing inwardly. The legs 56, 57 are joined by a pair of right angled horizontal braces 62, 63 which are welded or otherwise secured to the legs with the angles facing outwardly relative to the frame 10. Similarly, the legs 58, 59 are connected together by a pair of horizontal braces 64, 65 each formed of right angle stock with the angles facing outwardly relative to the frame 10. The sides of the frame 10 are enclosed by a pair of side panels 67, 68 on the right and left sides respectively. The side panels 67, 68 are mounted on the frame 10 by means of bolts which engage the corners of the legs such as the bolts 70, 71 of FIGURE 3 which engage the leg 59 and a bolt 72 which engages a right angle bracket 73 secured to the base plate 55. A similar right angle bracket 74 is mounted on the opposite side of the base plate 55 to receive a suitable panel engaging bolt, not shown.

As best seen in FIGURE 5 the carriage assembly 11 includes a pair of side plates 76, 77 which are secured together by an upper and a lower centrally located cross brace 78, 79 respectively and a rear cross brace 80. A pair of trunions 83, 84 are mounted on the side 76, 77 respectively of the carriage 11 for the purpose of rotatably supporting the tub or barrel 12. The trunions 83, 84 are positioned at an angle such as 55° relative to the bottom of the carriage 11 and are secured as by welding to the side plates so that the tub 12 may be lifted into a position in which a pair of cylindrical trunion arms 85, 86 of the tub 12 can fit within and rotatably engage the semi-cylindrical surfaces 88, 89 of the trunions 83, 84 respectively. A separate pair of trunions 91, 92 are positioned in engagement with the trunions 84, 83 respectively and are secured in engagement therewith by

means of suitable threaded bolts such as the bolts 93. The tub or barrel 12 may be secured in an upright position by securely tightening the trunion bolts 93. If however, it is desired to rotate the tub to discharge its contents one pair of threaded bolts 93 is loosened for example the forward or lower pair of bolts, one on each of trunions 91, 92, to permit the tub to be manually rotated by means of a pair of handles 94. The carriage side plates 76, 77 are provided with centrally located apertures 97, 98 respectively in which apertures are mounted the previously mentioned bushings or bearings 25, 26 respectively for rotatably supporting the drive shaft 24. The bushings 25, 26 are secured to the side plates by suitable means such as by bolts 101. The carriage 11 is provided with a weight 103 mounted on rear brace 80 which statically balances the tub 12 relative to the bearings 25, 26 when the tube is empty.

The carriage 11 and the counterpoise or side plates 15, 16 constitute the vibratory portions of the apparatus which are driven in an orbital, vertical path by means of 20 the drive shaft 24, the motor 22, the connecting belt 30 and pulleys 27, 28. The vibratory system is mounted in the frame 10 by means of a number of resilient shear-type bushings. For example, the counterpoise or side plate 15 is mounted by means of a pair of horizontally extending bushings 105, 106 each secured to an outwardly facing, vertically extending surface of the cross member 65 by means of a bolt such as bolts 107 and the opposite end of the bushing is secured to the counterpoise 30 15 by means of a bolt such as the bolt 108. Similarly the lower end of the side plate 15 is resiliently mounted on the cross members 64 by means of a pair of resilient shear-type bushings 109, 110 each held by a pair of bolts 107, 108. These bushings will be subsequently described in detail. The counterpoise or side plate member 16 is mounted from the frame 10 by means of four resilient shear-type bushings 112, 113, 114 and 115 each sewn by a pair of bolts 107, 108. These bushings are also connected to the outwardly facing surfaces 40 of the horizontal cross members 62, 63 in a manner similar to the bushings 105, 106, 109 and 110. The left side 76 of the carriage 11 is mounted by four shear bushings 116, 117, 118 and 119 to the legs 58, 59 of the frame 10. Similarly, the carriage side plate 77 is mounted on 45 the legs 56, 57 by means of pairs of shear-type resilient bushings 120, 121, 122 and 123. Because the resilient bushing and flexible belt 30 constitute the only physical connections between the frame 10 and the vibratory assembly including the carriage 11, the counterpoise plates 50 15, 16, and the drive shaft 24 and because the vibratory assembly is dynamically balanced, the vibratory assembly imparts very little vibration to the frame 10.

The details of the resilient bushings are best seen in FIGURES 7A and 7B which are fragmentary views, to 55 an enlarged scale, relative to FIGS. 2-6 showing the connections between the carriage side plate 76 and the frame leg 59 and between the frame horizontal brace 64 and the counterpoise member 15 respectively. In FIGURE 7A, the resilient bushing 116 is mounted between the 60 carriage side plate 76 and the frame leg 59 by means of a nut and bolt assembly. The resilient bushing 116 carries a cup shaped or concaved plate 125 which is recessed in an preferably vulcanized to the end of the rubber, or other resilient material, portion 126 and the cup shaped member 125 is welded or otherwise secured to a nut 127. The inner surface of the nut is threaded at 128 and receives the bolt 107 which passes through a lock washer 131 and the side plate or carriage side 76. The 65 opposite end of the resilient bushing 116 also carries a concave plate 132 which is identical to the plate 125. Plate 132 is welded or otherwise secured to a hexagonal type nut 133 which is threaded at 134 to receive an elongated bolt 108. A spacer block 136 is mounted between the frame leg 59 and the rubber portion 126 of the bush-

ing 116 so that the same size of shear type rubber bushing can be employed throughout the vibratory system of the finishing apparatus. Thus the resilient bushing 116 is identical in size, shape and construction with the rubber bushing 106 shown in FIGURE 7B and employed to mount the counterpoise plate 15 on the frame side member 64. Spacer blocks such as spacer block 136 are employed between each of the shear-type resilient bushings 116, 117, 118 and 119 and 120, 121, 122, 123 and the respective leg member to which they connect. A spring type lock washer 137 is employed between the bolt 108 and the frame leg 59.

The counterpoise plates 15, 16 are coupled to the drive shaft 24 by means of a pair of bearing 129, 130. As best seen in FIG. 6, the general configuration of the drive shaft 24 is substantially identical to the general configuration of the drive shaft shown in my application, Serial No. 357,212, filed April 3, 1964. In other words, the central portion 138 of the drive shaft 24 has a diameter on the major center line of the drive shaft 24 and a first pair of eccentric portions 139, 140 on opposite sides of the central portion 138 and adjoining thereto, which portions are eccentric with regard to the major center line in one vertical direction and rotatably engage bearings 25, 26 respectively, in the carriage 11. A second pair of eccentric sections 141, 142 are positioned outwardly from the previously mentioned eccentric portions 139 and 140, respectively, and have an eccentricity equal to and in the opposite direction from the eccentric sections 139, 140. The outer section 144 of the drive shaft 24 is concentric with the major center line and pulley 27 is mounted on section 144 by suitable means such as by a spline and key arrangement, not shown.

The finishing apparatus has a liquid circulating system which includes means for supplying a fluent compound mix to the tub or barrel 12. Depending on the type of compound supplied, the compound may deburr, burnish or finish the workpieces placed in the tub 12. The apparatus also includes means for rinsing the tub with clean fluid such as fresh water and for discharging the rinse to the drain during or after the operating cycle. The tub 12 is provided with a drain aperture 146 in the bottom thereof and has an angle bracket 147 welded or otherwise secured to the bottom of the tub 12 in a position of alignment with the aperture 146 and a plug 148 is mounted on the bracket 147 by means of a threaded rod 149 and handle 150 for movement into a fluid sealing relationship around the aperture 146. When it is desired to drain the tub 12 or to circulate the fluid through the tub 12, the handle 150 is manually rotated to move the plug 148 away from aperture 146 to permit the fluid to flow into the reservoir 20. The reservoir 20 includes a generally rectangular tank 151 and a generally rectangular tank cover assembly 152. The tank cover assembly is provided with a funnel-like member 153 adjacent the forward end of the cover assembly 152 and provided with an elongated transverse slot 155 which communicates with the tank 151. Because this slot 155 is in the rearward portion of the funnel 153, the slot is positioned to communicate with a drain catch which will be subsequently described and located in the forward end of the tank 151 or with the main reservoir section of the tank 151. The tank cover assembly 152 is longer than the tank 151 and is provided with a downwardly extending flange 154 which extends beyond the tank 151 to permit the tank cover 152 to slide longitudinally relative to the tank 151. Thus the tank cover 152 can assume two terminal positions as indicated by the two dotted outlines in FIGURE 2. In the forward position, or leftward position as viewed in FIG. 2, the tank cover mounted on funnel 153 controls, the flow of the fluid from the tank 12 or tub 12 such that it is discharged to a drain catch and then to a drain pipe whereas in the rearward funnel position, the fluid from the tank or tub 12 flows into a main res-

ervoir and is returned or recirculated by means of a pump, which will be subsequently described, to the tank or tub 12. The tank 151 includes a drain catch 157 formed in the forward end of the tank 151 by means of a right angled partition cooperating with the side walls and the front wall of the tank 151. A drain pipe 158 communicates with the drain catch 157 and extends through a baffle 159 positioned laterally across the tank 151 and also extends through the rear wall 160 of the tank 151. If the cover 152 of the reservoir 20 is positioned in its rear terminal position or positioned to the right as viewed in FIGURE 2, then the elongated slot 155 is behind the drain catch 157 such that fluid flowing from the tub 12 through the outlet 146 flows into the funnel 153 and into a settling chamber of the tank 151 to the left of the baffle 159. When sufficient fluid has flowed into this portion of the reservoir, it overflows the baffle 159 which is shorter than the sidewalls, and flows into the rear section which contains a submersible pump 164. The pump 164 has an intake 165 in communication with its periphery and an inlet pipe 166 which is connected to the source of clean water. The pump is also provided with a solenoid actuated valve, not shown, which can be employed selectively to connect the intake 20 side of the pump with either the clear water inlet conduit 166 or the compound mix inlet 165 within the rearward chamber of the tank 151. In either event, the pump supplies liquid through a pipe or tube 166 to the top of the tank or tub 12. Preferably, the switches 17, 18 and timer 19 are connected such that when the timer 19 is in "HOLD" position or dialed to a cycle time, either the machine motor 22 or the pump 164 can be operated. They are also connected so that when the timer 19 times out and goes to "OFF" position, everything is deenergized.

In order to provide for lubrication of the carriage bearings 25, 26 a pair of grease lines 170, 171 are provided each of which communicates with one of these bearings and terminates with a grease line inlet fitting, such as fittings 173, 174. Bearings 129, 130 are provided with grease fittings, not shown, accessible by removing side panels 67, 68.

In accordance with the patent statutes, the principals of the present invention may be utilized in various ways, 45 numerous modifications and alternations being contemplated, substitution of parts and changes in construction being resorted to as desired, it is understood that the embodiment shown in the drawings and described above is given merely for purposes of explanation and illustration without intention to limit the scope of the claims to the specific details disclosed.

What is claimed is:

1. A vibratory device for finishing articles comprising: frame means; counterpoise means including a pair of counterpoise plates; resilient means mounting each of said counterpoise plates within said frame means; a carriage; resilient means mounting said carriage within said frame means and between said counterpoise plates; eccentric means rotatably channeled in said carriage and in said counterpoise; means mounted on said frame for driving said eccentric means and coupled thereto in driving relationship; and tub means mounted in said carriage on one side of said eccentric means and a counterweight mounted in said carriage on the other side of said eccentric means from said tub means balancing said tub means.
2. The combination according to claim 1 wherein said resilient means comprise a plurality of substantially cylindrical shear-type bushings of resilient material each hav-

ing a concave metallic cup on the opposite ends thereof and fastening means secured to each of said concave cups.

3. The combination according to claim 1 wherein said tub means comprises a substantially cylindrical tub mounted with its axis substantially horizontal and having an aperture in the curved surface for the discharge of fluent material and wherein said apparatus includes a reservoir positioned beneath said tub for receiving said fluent material.

4. The combination according to claim 3 wherein said reservoir includes a tank and cover means slidably mounted on said tank, said cover means including funnel means, said tank including a drain catch portion, a reservoir portion, and an overflow portion communicating with said reservoir portion, said cover being slidable between a position in which said funnel means communicates with said drain catch portion and a position in which said funnel means communicates with said reservoir portion.

5. In a vibratory finishing apparatus the combination comprising:

- a generally rectangular frame including a plurality of vertically extending legs;
- a pair of counterpoise plates, each resiliently connected to said frame and positioned within said frame;
- a carriage resiliently mounted on said frame between said plates;
- a tub supported in said carriage for receiving the workpieces to be finished; and
- drive means including a shaft having first and said second pairs of eccentric members thereon, said first pair being rotatably coupled to said carriage, said second pair being rotatably coupled to said plates.

6. The combination according to claim 5 further comprising:

- a fluid reservoir positioned beneath said tub, said tub having an aperture therein and closure means for closing said aperture and manual means for opening said closure means, said reservoir including,
- a tank and a slidable top on said tank and having a discharge opening therein for discharging fluid into said reservoir, said tank including a drain catch, a settling chamber and an overflow chamber, and,
- a pump having a discharge nozzle communicating with said tub and having an inlet nozzle communicating with said overflow chamber.

7. The combination according to claim 6 including discharge means communicating with said drain catch.

8. In a vibratory finishing apparatus, the combination comprising:

- a generally rectangular frame including a plurality of vertically extending legs and the plurality of horizontal members connecting said legs;
- means resiliently mounting a pair of counterpoise plates on said horizontal members and within said frame;
- a carriage;
- resilient means mounting said carriage on said legs between said counterpoise plates;
- a drive shaft having eccentric portions thereon and extending through said counterpoise plates and said carriage and rotatably journaled therein by means of pairs of said eccentric portions;
- a tub rotatably mounted on said carriage receiving the workpieces to be finished; and
- and drive means for driving said drive shaft to vibrate said tub through an orbital path.

9. The combination according to claim 8 wherein said drive shaft is positioned centrally of said carriage, said tub being positioned adjacent one end of said carriage and wherein said carriage includes a counterweight mounted on the opposite end of said carriage from said tub for balancing said tub.

10. In a vibratory finishing apparatus, the combination comprising:

- a generally rectangular frame including a plurality of vertically extending legs;
- a pair of counterpoise plates, each resiliently connected to said frame and positioned within said frame;
- a carriage resiliently mounted on said frame between said plates;
- a cylindrical tub rotatably mounted on said carriage with its axis substantially horizontal, having an opening in the side thereof for receiving workpieces to be finished and having a fluent material discharge means therein; and
- drive means including a shaft having first and second pairs of eccentric members thereon said first pair being rotatably coupled to said carriage, said second pair being rotatably coupled to said plates.

11. The combination according to claim 10 including a fluent material system including:

- means for supplying fluent material to said tub;
- means for draining said fluent material from said tub and discharging same; and
- means for recirculating said fluent material.

12. The combination according to claim 10 wherein said frame includes a plurality of braces connecting said legs and wherein said counterpoise plates are resiliently mounted on certain of said braces.

13. In a vibratory finishing apparatus, the combination comprising:

- a generally rectangular frame including a plurality of vertically extending legs and a plurality of cross-braces connecting said legs;
- a pair of counterpoise members within said frame;
- a plurality of shear-type resilient bushings and fastener means mounting each of said bushings between said frame and said counterpoise members;
- a carriage having a tub and a tub counterweight thereon;
- a plurality of shear-type resilient bushing assemblies supporting said carriage on said frame and within said counterpoise members;
- a drive shaft having a first and a second pair of eccentric portions thereon, said pairs of eccentric portions being of equal eccentricity and being diametrically opposed;
- a first pair of bearing means mounted on said carriage and rotatably engaging said first pair of eccentric portions;
- a second pair of bearing means mounted on said counterpoise members and rotatably engaging said second pair of eccentric portions; and
- motor means for rotating said drive shaft.

14. The combination according to claim 13 wherein said tub has an opening therein for receiving workpieces and fluent material discharge means, said combination further comprising:

- means for supplying fluent material to said tub;
- means for draining said fluent material; and
- means for recirculating said fluent material.

15. The combination according to claim 14 wherein said means for draining said fluent material includes a tank, cover means slidably mounted on said tank, said cover means including a funnel communicating with said tank and a drain catch in said tank.

16. The combination according to claim 15 wherein said recirculating means includes a settling chamber in said tank, an overflow chamber in said tank, and pump means communicating with said overflow chamber.

17. In a vibratory finishing apparatus having a frame, a pair of counterpoise means, a carriage including a workpiece supporting tub and vibratory drive means, the combination comprising:

- a plurality of resilient shear-type bushings, each having a pair of metal plates secured to opposed vertical surfaces thereof; and

fastener means connecting certain of said metal plates to said frame and certain other of said metal plates to said counterpoise means and connecting the remaining metal plates to said carriage.

18. In a vibratory finishing apparatus having a frame, 5 a pair of counterpoise means, a carriage with a tub thereon and vibratory drive means, the combination comprising: a plurality of elongated, shear-type bushings, each having concave metal plates, on opposite ends thereof and fastening means on each of said plates; first bolt means connecting certain of said fastening means to said frame;

second bolt means connecting others of said fastening means to said counterpoise means; and third bolt means connecting still others of said fastening means to said carriage.
